UNITED STATES PATENT OFFICE

113,712

DESIGN FOR A BUN SERVER

Robert H. Moebus and Jeanne V. Moebus,
Omaha, Nebr.

Application December 30, 1938, Serial No. 82,090

Term of patent 14 years

To all whom it may concern:

Be it known that we, Robert H. Moebus and Jeanne V. Moebus, citizens of the United States, residing at Omaha, in the county of Douglas and State of Nebraska, have invented a new, original, and ornamental Design for Bun Servers, of which the following is a specification, reference being had to the accompanying drawing, forming part thereof.

Figures 1 and 2 are side elevational views at right angles to each other of a bun server, showing our new design,

Figure 3 is a top plan view.

We claim:

The ornamental design for a bun server, as shown.

JEANNE V. MOEBUS.
ROBERT H. MOEBUS.
